UNITED STATES PATENT OFFICE.

WILLIAM EVANS, OF YOUNGSTOWN, OHIO.

SAFETY HANDLE DEVICE.

Application filed August 27, 1926. Serial No. 131,976.

The object is the provision of a simple means for effectively holding an implement, such as a hammer, hatchet, axe or the like on the handle therefor, in which a bendable 5 yoke member is let in one side and along the edges of the eye end of the hammer, and in which the arms of the yoke are bent against the outer face of the implement, so that the handle and head of the implement 10 are effectively associated without the employment of wedges or analogous devices.

To the attainment of the foregoing, the invention consists in the improvement as hereinafter described and definitely claimed.

15 In the drawings:

Figure 1 is a side elevation, with parts in section, to illustrate the application of my improvement.

Figure 2 is an end view of a hammer provided with the improvement.

Figure 3 is a perspective view of the eye end of the handle for the hammer.

Figure 4 is a perspective view of the improvement.

25 In the showing of the drawings I have illustrated my improvement employed for holding the head and handle of a machinist's hammer associated, but obviously the improvement may be successfully employed 30 in connection with other types of similar implements.

The handle 1 has what I will term its eye end 2, provided on one of its sides with a transverse slot 3, the said slot merging into 35 longitudinal slots 4 on the opposite edges of the said end of the handle. Received in these aligning slots there is the yoke mem-

ber that constitutes the improvement. The yoke is formed from a strip of flat bendable metal, the connecting element 5 of which 40 having its ends bent laterally, as at 6, and from thence extended to provide parallel arms 7. The part 5 is received in the slot or opening 3, the arms 7 being received in the slots or openings 4. It should be stated 45 that the arms 7 are of a greater length than the slots 4 so that when the end 2 of the handle is inserted in the eye of the hammer 8, the projecting ends of the arms 7 may be bent in opposite directions against the outer 50 face of the said head, and thereby effectively hold the head and handle associated with-out the employment of wedges or analogous means.

Having described the invention, I claim:— 55

A means for holding a handle on a hammer head in which the eye end of the handle has one of its sides provided with a groove that communicates with longitudinal grooves that enter from the outer end of the said eye 60 end of the handle, and comprising a flat yoke whose central portion is designed to be received in the first mentioned groove, the ends of the said central portion being bent angularly and extended to provide parallel 65 arms which are received in the longitudinal grooves of the handle and project therebeyond and the ends of the arms designed to be bent against the outer face of the hammer head when the end of the handle is inserted through the eye of the said head. 70

In testimony whereof I affix my signature.

WILLIAM EVANS.
